UNITED STATES PATENT OFFICE

2,253,180

ELECTRIC VALVE EXCITATION CIRCUITS

Albert W. Hull, Schenectady, N. Y., assignor to
General Electric Company, a corporation of
New York

Application September 1, 1939, Serial No. 293,076

8 Claims. (Cl. 175—363)

My invention relates to electric valve circuits and more particularly to control or excitation circuits for energizing the control members of electric valve apparatus.

Where electric valve apparatus of the type employing immersion-ignitor control members or make-alive control members is used, it has been found desirable in many instances to supply only unidirectional impulses of current to the control members to initiate the arc discharge. In electric valve apparatus of this nature, disclosed and claimed in U. S. Letters Patent No. 2,069,283, granted February 2, 1937, on an application of J. Slepian and L. R. Ludwig, it has been found that the life of the electric valve apparatus may be materially increased by transmitting only unidirectional current to the control members. The control members have an extremity extending below the surface of the pool cathode and may be constructed of a material having a specific electrical resistivity relatively large compared with that of the associated cathode. For example, the control members may be constructed of a material such as boron-carbide or silicon-carbide. In accordance with the teachings of my invention described hereinafter, I provide new and improved control circuits for electric valve apparatus of this nature which is of simple construction and arrangement and which affords precise and accurate control of the conductivity of the electric valve apparatus.

It is an object of my invention to provide new and improved electric valve translating apparatus.

It is another object of my invention to provide new and improved control or excitation circuits for electric valve means of the type employing make-alive or immersion-ignitor control members.

It is a further object of my invention to provide new and improved control or excitation circuits for electric valve means of the type employing make-alive electrodes and in which only unidirectional impulses of current are transmitted to the control members.

Briefly described, in the illustrated embodiments of my invention I provide new and improved control or excitation circuits for electric valve means of the type employing immersion-ignitor or make-alive control members. The electric valve apparatus is arranged to dispense with the use of separate auxiliary rectifying equipment, while nevertheless transmitting to the control members unidirectional impulses of current which render the electric valve means

conductive for a predetermined interval of time and in a predetermined order. Associated equipment, such as peaking devices, are connected in the excitation circuits to supply impulses of voltage to render the electric valves conductive precisely at the desired instants, and the electric valve means operate in conjunction with the peaking devices to transmit only unidirectional impulses of current to the control members.

For a better understanding of my invention, reference may be had to the following description taken in connection with the accompanying drawings, and its scope will be pointed out in the appended claims. Figs. 1 and 2 represent certain embodiments of my invention as applied to an electric valve rectifying circuit wherein an isolated collector or grid is interposed between the anode and cathode of the principal electric valve means to operate as the auxiliary rectifying device, and Fig. 3 represents certain operating characteristics thereof. Fig. 4 represents a still further modification of my invention in which the metallic enclosing receptacle of the electric valve means operates in conjunction with the insulated cathode to transmit unidirectional impulses of current to the control member of another electric valve in the group of electric valves.

Referring now to Fig. 1 of the drawings, my invention is there illustrated as applied to an electric valve translating circuit for transmitting power between an alternating current circuit 1 and a direct current circuit 2 through a transformer 3 having a plurality of primary windings 4 and a plurality of secondary windings 5, 6 and 7 which constitute an inductive network of electrically displaced windings. I provide a plurality of electric valve means 8, 9 and 10 associated with windings 5, 6 and 1, respectively, and which transmit unidirectional current. The electric valve means 8, 9 and 10 are preferably of the type employing an ionizable medium, such as a gas or a vapor, and each comprises a cathode 11 of the pool type. The cathode 11 may consist of mercury which, of course, constitutes a self-reconstructing cathode. Each of the electric valve means 8—10 comprises a make-alive or an immersion-ignitor control member 12 associated with the cathode 11 and which is constructed of a material such as boron-carbide or silicon-carbide having an electrical resistivity relatively large compared with that of the associated cathode. One of the electric valve means 8—10 may be provided with suitable arc initiating means in order to place the system in condition for operation. It will be appreciated by those skilled

in the art that any conventional arrangement for establishing an arc discharge may be employed. I also provide within the electric valve means 8-10 an insulated collector or grid 13 which may be interposed within the arc discharge path between the anode 14 and the cathode 11. It is not necessary that the collector or grid be an actual grid in construction or that it should be directly interposed between the cathode and the anode; it may have any form and any position provided that it is immersed in the ionized gas during the firing or conducting period of the electric valve. When the word grid is used, it is to be understood in this sense. The grid 13 is insulated with respect to the cathode 11 and its function is the establishment of a conducting path between itself and the cathode 11 at a predetermined time during its cycle of operation to effect energization of a control member of one of the other electric valves 9 or 10.

I provide a plurality of excitation circuits 15, 16 and 17 associated with electric valves 8, 9 and 10, respectively, and which transmit to the control members 12 impulses of unidirectional current to establish arc discharges within the electric valve means and thereby render the electric valve means conductive in a predetermined order or sequence. Each of the excitation circuits 15-17 comprises a suitable means for producing impulses of voltage, such as a saturable inductive device 18 including a core member 19, a primary winding 20 and a secondary winding 21 in which there is induced an alternating voltage of peaked wave form. The excitation circuits 15-17 may be energized from any suitable source of alternating current of proper frequency and which provides the desired phase relationship of the voltages to be impressed on the control members 12. The excitation circuits in the embodiment of my invention shown in Fig. 1 are shown as being energized from the alternating current circuit 1. A suitable phase shifting arrangement, such as a rotary phase shifter 22, may be interposed between the circuit 1 and the excitation circuits 15-17.

As a means for assuring that only unidirectional current is transmitted to the control members 12 and to dispense with the use of separate auxiliary rectifying equipment, I connect the secondary windings 21 of the saturable inductive devices 18 between the control member of one electric valve and the grid of that electric valve preceding it in the order of phase rotation. For example, the secondary winding 21 of the device 18 associated with electric valve 8 is connected across control member 12 of electric valve 8 and the grid 13 of electric valve 10 which precedes the electric valve 8 in the order of conduction. Likewise, the control member 12 of electric valve 9 is connected through the secondary winding 21 of the saturable device 18 in excitation circuit 16 to the grid 13 in electric valve 8, the electric valve 8 preceding the electric valve 9 in the order of phase rotation.

The operation of the embodiment of my invention illustrated in Fig. 1 will be explained by considering the system when it is operating as a polyphase rectifier to transmit direct current to the circuit 2 from the alternating current circuit 1. For the purpose of explaining the operation of the excitation circuits 15-17, it will be assumed that the voltages of the secondary windings 5, 6 and 7 of transformer 3 have a phase rotation corresponding to that order; that is, the voltages assume their respective maximum posi-

tive values in that order. Consequently, the electric valves 8, 9 and 10 will conduct current in that order and each will conduct current for 120 electrical degrees inasmuch as the windings 5-7

5 constitute a three phase system. As is well understood by those skilled in the art, each of the electric valves 8-10 will conduct current until the electric valve following it in the order of phase rotation is rendered conductive, at which

10 time current will be commutated to the electric valve which is rendered conductive by virtue of the fact that its anode is more positive in potential than that of the electric valve which was previously conducting. In the present instance,

15 the electric valves are rendered conductive by the transmission of current to the control members 12 to establish on the surface of the mercury pool cathode 11 a cathode spot, thereby establishing an arc discharge between the cathode 11

20 and the anode 14.

Each of the saturable inductive devices 18 or excitation circuits 15-17 produces an alternating voltage of peaked wave form. These voltages are displaced in phase by 120 degrees due to the connection of the primary windings 20 in the three phase circuit 1. However, due to the fact that each of the secondary windings 21 is connected in series relation with an arc discharge path of another electric valve, only unidirectional current will be transmitted to the control member. That is, since the secondary windings 21 are connected to the grids 13 of other electric valves, the other electric valves operate as rectifying units for the control members.

25 30 35 Consider the operation of the system when one of the electric valves, as for example electric valve 9, is to be rendered conductive during the 120 electrical degree period following the normal period of conduction of electric valve 8 and electric valve 8 has been conducting current. Consequently, the ionizable medium of the electric valve 8 is in an ionized state and current may flow between the cathode 11 and the grid 13. As a result, when the voltage induced in the sec-

ondary winding 21 of the inductive device in excitation circuit 16 increases sufficiently to transmit an appreciable current to the control member 12 of electric valve 9, substantially only unidirectional current will be transmitted to that

40 45 50 control member since the grid 13 and cathode 11 of electric valve 8 operate in effect as an auxiliary rectifier. As soon as the electric valve 8 becomes nonconductive by the commutation of current to the electric valve 9, the circuit for the

55 60 65 energization of the control member 12 of electric valve 9 will be interrupted since the mercury vapor of valve 8 becomes de-ionized. In this manner only unidirectional impulses of current are transmitted to the control members and the circuits for the energization of the control members are interrupted as soon as the electric valve is rendered conductive and current has been commutated to that valve. Since only unidirectional current is transmitted to the control member, the duty imposed on the control member is substantially reduced and the life of the electric valve means is greatly increased.

70 75 80 Where it is desired to assure that the potential of the control members 12 is always maintained positive with respect to that of the associated cathode 11, I provide, as shown in Fig. 2, means for introducing into the excitation circuits 15-17 voltages to assure that no inverse current flows between the control members 12 and the cathodes 11. I provide suitable means, such as trans-

formers 23, connected in excitation circuits 15-17 to impress on the control members 12 positive voltages to maintain the control members positive with respect to the cathodes 11. This voltage may be provided in a number of ways and I have chosen, for the purposes of illustration, to show alternating current means, such as transformers, energized from the alternating current circuit 1 through a suitable phase shifting device such as a rotary phase shifter 24 for energizing the transformers 23. The rotary phase shifter 24 is adjusted so that the voltage introduced into each excitation circuit is such that the resultant voltage impressed on each of the control members 12 is positive during the entire interval of time during which its associated excitation circuit is completed through the electric valve which precedes it in the order of phase rotation.

The manner in which the excitation circuits shown in Fig. 2 operate may be more fully understood by referring to the operating characteristics shown in Fig. 3. Curve A represents the voltage of peaked wave form produced by the saturable inductive device 18 in one of the excitation circuits, such as excitation circuit 16 associated with electric valve 9. It will be understood that the positive impulses of voltage represented by Curve A occur 360 electrical degrees apart. For example, the electric valve 9 is rendered conductive at times a and c. Furthermore, it will be understood that electric valve 9 conducts current only 120 electrical degrees during each cycle. Furthermore, it will be appreciated that the electric valve 8 is rendered conductive at time b and that the electric valve 8 conducts current during the interval b-c. During the interval of time that the electric valve 8 conducts it will be appreciated, by referring to the curves of Fig. 3, that an inverse voltage may be impressed on the control member 12 of electric valve 9 if no auxiliary equipment were employed. By the proper adjustment of the rotary phase shifter 24, the component of voltage introduced into excitation circuit 16 by transformer 23 may be adjusted in phase so that at all times during the interval b-c the resultant voltage impressed on control member 12 is positive. In this manner the transmission of inverse current between the control member 12 and the cathode 11 is prevented and the life of the electric valve is correspondingly increased.

Fig. 4 illustrates a simplified embodiment of my invention as applied to a system similar to that shown in Fig. 1 and corresponding elements have been assigned like reference numerals. Instead of employing separate auxiliary grids which cooperate with the cathodes to rectify the excitation currents transmitted to the control members, I employ electric valves 25, 26 and 27 which comprise metallic enclosing envelopes 28 and electrically insulated cathodes 29. The cathodes 29 may be insulated from the envelopes 28 by means of suitable insulating means, such as insulator rings 30, positioned between the upper portion of the envelopes and the cathodes. That is, the cathodes 29 are electrically insulated from the envelope 28. Accordingly, the envelope 28 may be employed as one electrode of an auxiliary rectifying unit. I connect the secondary winding 21 of each of the inductive devices 18 to the metallic envelope 28 of that electric valve preceding it in the order of phase rotation. One of the important features of this arrangement is the simplicity of construction and the incident re-

duction in cost by utilizing a simplified electric valve.

The operation of the embodiment of my invention shown in Fig. 4 is substantially the same as that explained above in connection with Fig. 1. Substantially only unidirectional current is transmitted to the control members 12. The rectification action is effected between metallic envelopes 28 and the insulated mercury pool cathodes 29 which operate as auxiliary rectifiers, and which effect completion of the excitation circuits for the control members 12 until the electric valve preceding it in the order of phase rotation has been rendered nonconductive by the commutation of current therefrom.

While I have shown and described my invention as applied to particular systems of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, an alternating current circuit, a direct current circuit, electric translating apparatus connected between said circuits and comprising an inductive network including a plurality of electrically displaced windings and a plurality of electric valves of the type employing an ionizable medium and each associated with a different one of said windings and each comprising an anode, a cathode, an immersion-ignitor control member associated with the cathode and means insulated from said cathode for establishing a conducting path to said cathode through said medium when said medium is ionized, and a plurality of means for supplying to the control members periodic impulses of unidirectional current and each comprising a source of current including a winding having one terminal in circuit with the control member of the associated electric valve and having the other terminal connected to the insulated means of that electric valve preceding it in the order of phase rotation.

2. In combination, an alternating current circuit, a direct current circuit, electric translating apparatus connected between said circuits and comprising an inductive network including a plurality of electrically displaced windings and a plurality of electric valve means each associated with a different one of said windings and each comprising an anode, a cathode, an immersion-ignitor control member associated with the cathode and a grid interposed in the arc discharge path between said anode and said cathode, means for supplying to the control members periodic impulses of unidirectional current comprising a plurality of saturable inductive devices each including a primary winding and a secondary winding, means for supplying alternating current to the primary windings, and means for connecting each of said secondary windings to the control member of the associated electric valve means and the grid of that electric valve means preceding it in the order of phase rotation.

3. In combination, an alternating current circuit, a direct current circuit, electric translating apparatus connected between said circuits and

comprising an inductive network including a plurality of electrically displaced windings and a plurality of electric valves of the type employing an ionizable medium and each associated with a different one of said windings and each comprising a metallic enclosing envelope, an anode, a cathode and an immersion-ignitor control member associated with said cathode, said cathode being insulated from said envelope, and a plurality of means for supplying to the control members periodic impulses of unidirectional current and each comprising a source of current including a winding having one terminal in circuit with the control member of the associated electric valve and having the other terminal connected to the envelope of that electric valve preceding it in the order of phase rotation, said envelope of that electric valve and the associated cathode serving as a rectifier to complete the circuit for the energization of said control member.

4. In combination, an alternating current circuit, a direct current circuit, electric translating apparatus connected between said circuits and comprising an inductive network including a plurality of electrically displaced windings and a plurality of electric valve means each associated with a different one of said windings and each comprising an anode, a cathode, an immersion-ignitor control member associated with the cathode and a grid insulated from said cathode and interposed in the arc discharge path between said anode and said cathode, means for supplying to the control members periodic impulses of unidirectional current, and means for connecting said last mentioned means between a control member of one electric valve and the grid of the electric valve preceding it in the order of phase rotation whereby a circuit is completed between said grid and the associated cathode to energize said control member.

5. In combination, an alternating current circuit, a direct current circuit, electric translating apparatus connected between said circuits and comprising an inductive network including a plurality of electrically displaced windings and a plurality of electric valves of the type employing an ionizable medium and each associated with a different one of said windings and each comprising an anode, a cathode, an immersion-ignitor control member associated with the cathode and means insulated from said cathode for establishing a conducting path to the cathode through said medium when said medium is ionized, and means connected in circuit with the control member of each of said electric valves and the insulated means of the electric valve preceding it in the order of phase rotation to maintain the potential of the control member positive with respect to the associated cathode during the entire period of conduction of that electric valve preceding it in the order of phase rotation.

6. In combination, an alternating current circuit, a direct current circuit, electric translating apparatus connected between said circuits and comprising an inductive network including a plurality of electrically displaced windings and a plurality of electric valves of the type employing an ionizable medium and each associated with a different one of said windings and each

comprising an anode, a cathode, an immersion-ignitor control member associated with the cathode and means insulated from said cathode for establishing a conducting path to the cathode through said medium when said medium is ionized, a plurality of excitation circuits for supplying to the control members periodic impulses of current to render said electric valves conductive in a predetermined order and during predetermined intervals of time, said excitation circuits each being connected between the control member of one electric valve and the insulated means of that electric valve preceding it in the order of phase rotation, and means for introducing into said excitation circuits components of voltage to maintain the potential of the control members positive with respect to the cathodes at least during the interval of time during which the respective excitation circuits are completed through the insulating means and the cathode of the electric valve preceding it in the order of phase rotation.

7. In combination, an alternating current circuit, a direct current circuit, electric translating apparatus connected between said circuits and comprising an inductive network including a plurality of electrically displaced windings and a plurality of electric valves of the type employing an ionizable medium and each associated with a different one of said windings and each comprising an anode, a cathode, an immersion-ignitor control member associated with the cathode and means insulated from said cathode for establishing a conducting path to the cathode through said medium when said medium is ionized, a plurality of excitation circuits each comprising a saturable inductive device having a primary winding and a secondary winding, each of said secondary windings being connected between the control member of one electric valve and the insulated means of that electric valve preceding it in the order of phase rotation, means for supplying to the primary windings alternating current, and a plurality of means for introducing into said excitation circuits components of voltage to maintain the potential of the control members positive with respect to the cathodes during intervals of time immediately preceding the normal intervals of conduction of the electric valve means.

8. In combination, an alternating current circuit, a direct current circuit, electric translating apparatus connected between said circuits and comprising an inductive network and an electric valve means having an anode, a cathode and a control member of the immersion-ignitor type associated with said cathode, an excitation circuit for energizing said control member comprising means for producing an alternating voltage of peaked wave form, and means including rectifying means for introducing into said excitation circuit a component of voltage sufficient to neutralize a predetermined portion of the negative half cycles of said voltage of peaked wave form so that the resultant voltage impressed on said control member by said excitation circuit during a predetermined portion of the anode-cathode voltage is unidirectional.
